UNITED STATES PATENT OFFICE

NATHAN KASDAN, OF NEW YORK, N. Y.

MASCARA CASE

Application filed September 16, 1931. Serial No. 563,211.

This invention relates to a mascara case and has for its object to provide a device of this class which is convenient to handle, simple to construct and easy to clean and replace or refill with a new cake of cosmetic material.

Referring to the drawings:

Fig. 1 shows one embodiment of this invention with the hinged cover raised.

Fig. 2 is a section on the line 2—2 of Fig. 1.

Fig. 3 is a perspective of a metal stamping for holding the applicator brush.

Fig. 4 is the metal receptacle for holding the cake of mascara.

The metal box 10 is shown as being provided with a cover portion 11 hinged thereto and provided on the inside with a mirror 12 secured within the cover. Within the main body portion of the box 10 is a metal receptacle 13 in which is placed a cake of mascara 14, or other type of cosmetic.

A second metal receptacle or stamping 15 is provided with a longitudinal depression therein for holding an applicator brush 16 provided with bristles 17 and the handle portion indicated. The sides of the stamping 15 are bent down at 18 and 19 to form downturned flanges which support the stamping 15 in the box 10.

The longitudinal depression is enlarged at 20 so that the brush handle may be grasped and withdrawn more easily. Riveted to the front side of the box 10 at 21 and carried on the inside of the front wall is the metal spring 22 carrying the cover latch 23. This latch 23 is actuated by the projection shown as extending out through the front wall of the box 10 and said latch 23 engages the inside of an outwardly pressed portion 24 in the cover.

The stamping 15 and receptacle 13 are so shaped as to wedgely or substantially tightly fit within the box. The top surface of the stamping 15 is enameled so that this surface may be easily cleaned and there will be no tendency for moisture from the brush to rust or corrode the surface of the depression in which the brush is carried. The downturned flanges 18 and 19 as well as the side walls of the box are each slightly yieldable whereby a good fit may be obtained for the receptacle

13 and stamping 15 within the box 10. To replace or refill the box the receptacle 13 is removed and either cleaned or refilled with a new cake 14 or else a new box 13 containing a new cake 14 is inserted. The stamping 53 15 is readily removed for cleaning. It will be seen that the downturned flange 18 is cut away at one portion adjacent the brush bristles 17. Also the opposite flange 19 is cut away centrally in the manner indicated to 60 provide a recess in which the cover latch and its spring may be movable. Since the receptacle 13 is generally renewable with the mascara cake 14, such receptacle is not generally enameled and it has been found that 65 only the top surface of the stamping 15 need be so protected by enamel.

I claim:

1. A mascara case comprising a metal box having a hinged cover provided on the inside with a mirror, the box containing a removable metal receptacle for a cake of mascara, a second metal receptacle contiguous the first and provided with a longitudinal depression shaped to receive a small narrow 70 applicator brush, said depression being enlarged adjacent an end thereof to facilitate grasping the handle portion of said brush, the brush and the depression being so proportioned that the bristles of the brush are 75 below the top of the mascara receptacle when the brush is laid on its side in said depression, and a latch for holding the cover of said box closed.

2. A mascara case comprising a metal box 85 having a hinged cover provided on the inside with a mirror, the box containing a removable metal receptacle for a cake of mascara, a second metal receptacle contiguous the first and provided with a longitudinal depression 90 shaped to receive a small narrow applicator brush, said depression being enlarged adjacent an end thereof to facilitate grasping the handle portion of said brush, the brush and the depression being so proportioned that the 95 bristles of the brush are below the top of the mascara receptacle when the brush is laid on its side in said depression, a latch for holding the cover of said box closed, the second mentioned metal receptacle containing the 100

brush being a removable stamping wedgingly fitted and held between the first receptacle and the walls of the box and provided with downturned lateral flanges supporting said 5 second receptacle, one of said flanges being cut away to provide space for the brush bristles, and the opposite downturned flange being cut away to provide space for movement of the cover holding latch, said second mentioned receptacle being enameled on the top 10 side thereof and in said depression.

3. A mascara case comprising a metal box having a hinged cover provided on the inside with a mirror, the box containing a removable metal receptacle for a cake of mascara, a second metal receptacle contiguous the first and provided with a longitudinal depression shaped to receive a small narrow applicator brush, said depression being enlarged adjacent an end thereof to facilitate grasping the handle portion of said brush, the brush and the depression being so proportioned that the bristles of the brush are below the top of the mascara receptacle when the 25 brush is laid on its side in said depression, a latch for holding the cover of said box closed, the second mentioned metal receptacle containing the brush being a removable stamping wedgingly fitted and held between the 30 first receptacle and the walls of the box and provided with downturned lateral flanges supporting said second receptacle, one of said flanges being cut away to provide space for the brush bristles, and the opposite downturned flange being cut away to provide space for movement of the cover holding latch, the sides of said box and the sides of the stamping being slightly yieldable to facilitate clamping of said stamping or second mentioned receptacle in position contiguous the 35 first mentioned receptacle.

NATHAN KASDAN.
